UNITED STATES PATENT OFFICE

161,798

NECKTIE

Ernest Spielmann, New York, N. Y.

Application November 16, 1950, Serial No. 13,005

Term of patent 14 years

(Cl. D3—16)

To all whom it may concern:

Be it known that I, Ernest Spielmann, a citizen of the United States and residing at New York, in the county of New York and State of New York, have invented a new, original, and ornamental Design for Necktie, of which the following is a specification; reference being had to the accompanying drawings, forming part thereof, and in which

Fig. 1 is a perspective view of the necktie, showing my new design,

Fig. 2 is an edge elevation thereof, and

Fig. 3 is a perspective view showing the tie in wear.

I claim:

The ornamental design for a necktie, substantially as shown.

ERNEST SPIELMANN.
